ANDREWS COMPANY, OF ATTLEBORO, MASSACHUSETTS, A CORPORATION
OF MASSACHUSETTS.

BUCKLE.

1,399,343.

Specification of Letters Patent.

Patented Dec. 6, 1921.

Application filed March 30, 1921. Serial No. 456,921.

To all whom it may concern:

Be it known that I, WALTER E. GUYOT, a citizen of the United States, residing at Attleboro, in the county of Bristol and State of Massachusetts, have invented certain new and useful Improvements in Buckles, of which the following is a specification.

This invention relates to that class of buckles that have a pivoted part which by wedge or cam action clamps a belt or strap to hold it against tension, the arrangement being such that the engaging or retaining action may be at any desired place on the strap.

It is an object of the invention to so form the parts of such a buckle that the pull of both the adjustably-held and fixedly-held portions of a strap act directly on the clamping member to cause it to hold.

A further object of the invention is to pivotally support a clamp member in the body of the buckle, the clamp being provided with two spaced-apart, rigid clamping edges located at different distances from the pivotal axis of said member, each edge being adapted to engage and clamp a belt independently of the other, the different clamping lengths of this edge rendering it capable of engaging belts of widely different thicknesses.

Another object of the invention is to arrange the parts in such manner that the clamping member easily may be forced to and released from clamping position.

When read in connection with the description herein the details and characteristics of the invention will be apparent from the accompanying drawing forming part hereof, wherein an embodiment of the invention in a belt-buckle is disclosed, for purposes of illustration.

While the disclosures herein exemplify what now is considered to be a preferable embodiment of the invention, it is to be understood that it is not the intention to be limited necessarily thereto in interpretation of claims, as modifications and adaptations within the limits of the claims can be made without departing from the nature of the invention.

Like reference characters refer to corresponding parts in the views of the drawing, of which—

Figure 1 is a view of the rear side of the buckle.

Fig. 2 is a longitudinal sectional view on the line 2—2 of Fig. 1.

Fig. 3 is a view of the clamping member as seen when looking at an end of the buckle.

Fig. 4 is an enlarged sectional view of 60 the clamp member showing a bail so constructed that it may be employed to lift or pry the clamp from clamping position.

Fig. 5 is an enlarged view of the clamping member in position to clamp a comparatively thick belt by the edge having the shortest gripping radius.

Fig. 6 is a similar view illustrating the clamp as engaging a belt of medium thickness by the combined action of both its long 70 and short clamping edges.

Fig. 7 is a detail illustrating the clamp as engaging a thinner belt by the clamping edge having the longest clamping radius.

Fig. 8 is a view illustrating the arrangement of the clamp folded into L-shape in cross-section by which shape the clamp is permitted to be raised clear of the belt by a rearward pressure on the bail the latter remaining substantially parallel with the 80 buckle body.

Having more particular reference to the drawing, 5 designates the front plate or body portion of a buckle. Oppositely-disposed flanges 6 extend at substantially right 85 angles readwardly from the front plate. With that plate they afford a guideway for the strap or the like to be adjustably held. Preferably the plate and flanges are formed integrally of sheet metal.

Near one end of the buckle guide lips 7 may extend inwardly from the flanges in separated relation to the front plate to act as a guide for the entering strap or belt into the buckle and to hold it against the 95 plate.

At or near the end of the buckle there is mounted a clamp member 8 which is carried by pintles 9 extending from the ends thereof into seats in the flange 6.

This clamp member is shown as being formed or folded substantially into L-shape in cross section and is arranged to swing on its pivots, the lower edge 11 of the standard and the outer edge 18 of the base of the L 105 providing two separate and distinct rigidly clamping edges located at different distances from the pivotal center, whereby these edges are adapted to independently engage and clamp belts of different thicknesses 110

against the inner face of the buckle body, or they may act in unison to jointly engage and clamp a belt of a given thickness.

In my present construction the clamping edge 18 is located at a greater distance from the swinging center than is the clamping edge 11, and therefore, when a comparatively thick belt is placed in the buckle the edge 11 will engage the belt and bind it in the body of the buckle, as best illustrated in Fig. 7.

Substantially on the opposite side of the pivotal axis the clamp 8 has oppositely-disposed pintles 12, which afford means of pivotally connecting to that member a bail or other suitable part arranged to act as a lever, the same being arranged to have an end portion of a strap or the like secured thereto. In the embodiment shown this bail member is cut from sheet-stock and is folded to form a cross-bar 13 arranged to have a portion of a strap or the like passed therearound the side portions 14 thereof having enlarged terminal portions 15 formed with seats or eyes into which the pintles 12 extend.

On the side of the pivotal axis toward the crossbar 13 each of the terminal portions 15 has an enlargement or shoulder 16 positioned to engage the adjacent edge of the clamp 8 to assist in moving the edges 11 or 18 against the strap or the like to be held adjustably in the buckle when the cross bar 13 is pressed toward the front plate of the buckle. Then again this shoulder serves as a stop to limit the outward swing or releasing motion of the clamp relative to the bail.

By this construction as best illustrated in Fig. 8, by folding the clamp into L-shape in cross-section I am enabled to obtain two distinct clamping edges and at the same time I am enabled as best illustrated in Fig. 8, to swing the clamp clear of the belt by a rearward pressure on the bail and still maintain the bail in a plane substantially parallel to that of the body of the buckle to permit a free entrance of the belt into the buckle and at the same time take up the minimum operating or working space on the inner side of the buckle.

When the gripping edges have thus been brought into engagement the hold or grip on the adjustable end of the strap is increased both by the pull or stress thereof in one direction and by the pull or stress in the other direction of the part fixedly secured to the cross-bar 13, whereby a reliable hold is maintained on the adjustably-held part.

It is found in practice that when a belt is drawn tightly around the body that its tension serves to draw the clamp member firmly into gripping or binding position requiring some considerable strength to release it and to accomplish this releasing action in a simple and practical way I have

provided a rearward and downwardly extending lug 17 on the rear side of the terminal projections 15 of the bail which lugs serve a double purpose; first, they engage the back of the clamp and by lifting the bail relative to the body a considerable leverage is obtained by which this clamp is pried loose from its clamping or gripping position on the belt to free the belt and permit it to be removed from the buckle. In some instances where the belt is very tight the front edge of the buckle is lifted outwardly relative to the bail, which action also serves to cause the bail to pry the clamp free from its clamping position.

Another object of this rearwardly and downwardly extending lug 17 is to control the backward swing of the clamp to positively prevent an excessive tension on the adjustable end of the belt, from drawing the clamp past its maximum gripping center.

For instance in some cases where the gripping edge 18 may be engaging a comparatively thin belt if it were not for the stop a heavy or unusual strain on the belt might draw this edge past its gripping center and so release the belt entirely.

My improved buckle is extremely simple and inexpensive and practical in construction, is strong and durable and is very effective in its action and operation and by its use belts of widely differing thicknesses may be tightly bound and held therein.

The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. A buckle comprising a body portion, a clamp member pivotally supported in said body and having two separated relatively rigid clamping edges located at different distances from the pivotal axis of said member, each edge being adapted to clamp a belt independently of the other edge whereby belts of widely different thicknesses may be retained in said body, and a free swinging bail member pivotally mounted on said clamp independent of the clamp-pivot and provided with means for limiting the relative swinging of said clamp.

2. A buckle comprising a body portion, a clamp member pivotally supported in said body to engage and bind the belt in the body, and a belt attaching member pivotally connected to said clamp, independent of the clamp-pivot and having one end free to swing and having means for limiting the gripping motion of said clamp to prevent its swinging beyond its maximum gripping point.

3. A buckle comprising a body portion, a

clamp plate folded into L-shape in cross-section and pivotally mounted in said body, said clamp having two spaced apart rigid clamping edges located at different distances from the pivotal axis of said member whereby they are adapted to operate independently to engage and bind belts of different thicknesses, and a bail member connected to said clamp to which the opposite end of the belt 10 may be connected.

4. A buckle comprising a body portion, a clamp plate folded into L-shape in cross-section and pivotally mounted in said body, said clamp having two spaced-apart rigid clamping edges located at different distances from the pivotal axis of said member whereby they are adapted to operate independently to engage and bind belts of different thicknesses, and a bail member pivotally mounted 15 on said clamp, independent of the clamp-pivot and adapted to be lifted to pry the clamp from clamping position.

5. A buckle comprising a body portion, a clamp plate folded into L-shape in cross section and pivotally mounted in said body, said 20

clamp having two spaced apart rigid clamping edges located at different distances from the pivotal axis of said member whereby they are adapted to operate independently to engage and bind belts of different thicknesses, a bail member pivotally mounted on said clamp independent of the clamp-pivot having one end free to pry the clamp from clamping position, and means also at the joint end of the bail for limiting the gripping movement of said clamp. 30

6. A buckle comprising a body portion, a clamp member pivotally mounted in said body and having two spaced apart rigid clamping edges located at different distances from the pivotal axis of said member, a belt-attaching bail pivotally connected at one end to said clamp independent of the clamping pivot and its opposite end being free to swing, and means for limiting the gripping motion of said clamp to prevent it from swinging beyond its maximum gripping point. 40

In testimony whereof I affix my signature.
WALTER E. GUYOT.
